CLAIM

The ornamental design for a mount, as shown and described.

DESCRIPTION

FIG. 1 is a front, side, and top perspective view of a mount embodying the new design.

FIG. 2 is a back, side, and top perspective view thereof.

FIG. 3 is a front view thereof.

FIG. 4 is a back view thereof.

FIG. 5 is a top view thereof.

FIG. 6 is a first side view thereof, the second side view being a mirror image.

FIG. 7 is a side, top, and front perspective view thereof.

FIG. 8 is a bottom, back, and side perspective view thereof.

FIG. 9 is a bottom, front, and side perspective view thereof; and,

FIG. 10 is a front, top, and side perspective view thereof. The broken lines showing a digital media player, cables, and a backside of a television form no part of the claimed design. The dot-dash lines form unclaimed boundaries of the claim, which together with the other broken lines form no part of the claimed design.
